GRID FOR AN ELECTRON DISCHARGE DEVICE

Cecil H. Green, Newark, N. J., assignor to International Communications Laboratories, Inc., Newark, N. J., a corporation of New York

Application June 25, 1932, Serial No. 619,307

5 Claims. (Cl. 250—27.5)

My invention relates to an improvement in electron discharge devices, and particularly to the type employing a cathode, an anode and a grid member for controlling the passage of an electron stream between the cathode and anode.

The main object of my invention is the construction of a grid member which is substantial and which will retain its position and form when subjected to intense heat during the operation of the electron device.

According to my invention the grid, which is preferably cylindrical in shape, is formed by crossing a plurality of wires, preferably of molybdenum, and twisting the wires together at the intersections or crossings so as to form a rigid screen or mesh. The wires at one end of the cylindrical screen are interwoven with openings in a base, or support, at the time the screen is being formed. Wires suitable for grid construction when spot-welded become brittle and are easily subject to breakage. Forming the grid with the wires twisted together at the intersections, or crossings, overcomes this defect and produces a rugged type screen which is not readily broken even with rough usage.

The method of making the grid according to my invention will be explained in the detailed description to follow:

Fig. 1 shows complete grid structure;

Fig. 2 shows a section through the mandrel from which the grid is formed;

Fig. 3 shows a portion of the mandrel;

Fig. 4 shows the first stage in construction of the grid in a developed form;

Fig. 5 shows a section of the grid in a developed form;

Fig. 6 shows an enlarged explanatory diagram of Fig. 5; and

Fig. 7 shows the manner in which the wires are twisted together.

Referring to Fig. 1, the grid, as shown at 25, comprises a screen or mesh formed by interweaving a plurality of wires in the manner to be explained later.

45 The grid wires are looped through, or interwoven with, the ring-shaped base 20. The supporting prongs 22, 23 and 24 attached to the ring are fastened to the base of the tube (not shown) in any manner well known in the art.

50 Referring to Figs. 2 and 3, a mandrel 30 is provided with a series of openings into which pins 11 to 18 are inserted. These pins fit snugly within the openings and are removable at will. One end of the mandrel is provided with the reduced portion 31 which fits within the ring support 20

when the wires are being interwoven with one another.

In starting the formation of the screen, or mesh, the first set of pins is inserted in the lower set of openings extending around the circumference of the mandrel 30, as shown in Figs. 1, 2 and 4.

In the present instance I have illustrated a screen formed of four lengths of wire made into loops and threaded through the openings 21 in 10 the ring 20, thus providing eight wires, 1 to 8, extending vertically, as shown in Fig. 4. After this operation the end 31 of the mandrel is inserted into the ring 20 and positioned so that the wires pass to the left of pins 11 to 18. The upper 15 ends of the wires 1 to 8 may be attached to a temporary securing or holding device fastened to the upper end of the mandrel 30 to retain them in position.

In forming the grid, wire 1 is first turned to 20 the right over pins 11 and 12 and twisted with wire 2 at pin 12, as shown in Figs. 5, 6 and 7.

Fig. 7 shows in detail the form of twist used. After the twist is made, wire 2 is again placed in a vertical position, as shown, and wire 1 is then 25 turned to the right over pin 13 and twisted with wire 3. Wire 3 is then placed in a vertical position and wire 1 continues on and is twisted with the remaining wires 4 to 8 in the same manner, after which it is looped with itself at pin 11, as 30 shown in Fig. 6; after which it is placed in a vertical position.

It will be noted that wire 1 is twisted with each wire at its respective pin in the lower set.

After this operation, a second set of pins is in- 35 serted in the second set of openings in the mandrel 30 and all of the wires which are now in a vertical position pass to the right of their respective pins in the second set.

Wire 2 is now turned to the left over pin 12 in 40 the second set, then over pin 11 in the second set and twisted with wire 1, after which wire 1 is placed in a vertical position.

Wire 2 is now turned over pin 18 and twisted with wire 8, after which wire 8 is placed in a 45 vertical position. This action is continued until wire 2 is twisted with each wire at its respective pin, after which it is looped with itself and placed in a vertical position.

A third set of pins is now inserted in the third 50 row or set of openings in the mandrel, after which wire 3 is turned to the right over pin 15 in the third row, then over pin 14 and twisted with wire 4.

This operation is continued until wire 3 is 55

twisted with each wire at its respective pin in the third row or set.

From the foregoing it will be noted that each of the wires, 1 to 8, will completely encircle the mandrel at a certain row of pins, and will be twisted with all of the wires during the encircling operation.

The grid may be extended to any desired length by continuing the interweaving of the wires in the manner described. The size and shape of the openings in the mesh, or screen, are determined by the position of the openings in the mandrel within which the pins are inserted.

In Figs. 5 and 6 the arrows indicate the direction the wires take during the formation operation. Fig. 6, for clearness, shows the encircling wires without twists.

After the grid has been interwoven to give the desired length, the ends are interwoven to form a reinforcing ring 26, as shown in Fig. 1, after which the loose or surplus ends are cut off. From the foregoing it will be seen that the grid is rigid and substantial and is only supported by the base 20 with which it is interwoven.

It is unnecessary to provide a support for the upper end of the grid.

As is common practice, well known in the art, the filament is positioned within the grid and the anode is positioned to surround the grid. The grid made according to my invention will not buckle or bulge to come in contact with the filament or anode when heated during the operation of the electron discharge device.

What is claimed is:

1. A grid electrode composed only of a plurality of turns of wire spaced apart by at least three peripherally spaced longitudinal wires intersecting and intertwined with said turns at the points of intersection, each longitudinal wire being continuous with a plurality of said turns, and successive turns serially included in the same longitudinal wire being separated by a number of

turns corresponding to the number of longitudinal wires.

2. A grid electrode composed only of a tubular base and a plurality of wires secured thereto and extending from one edge thereof in a direction parallel to the axis thereof, and one of said wires at each of a plurality of spaced points intermediate its ends extending peripherally to form a turn intersecting the longitudinal wires and fastened thereto at the points of intersection. 10

3. A grid electrode composed only of a tubular base and a plurality of wires secured thereto and extending from one edge thereof in a direction parallel to the axis thereof, and each of said wires at a point intermediate its ends extending peripherally to form a turn intersecting the longitudinal wires and fastened thereto at the points of intersection, said turns being spaced longitudinally of said wires thereby to form a self-supporting tubular electrode. 20

4. A grid electrode composed only of a tubular base and a plurality of wires secured thereto and extending from one edge thereof in a direction parallel to the axis thereof, and each of said wires at each of a plurality of spaced points intermediate its ends extending peripherally to form turns intersecting said wires and fastened thereto at the intersecting points, successive turns in each wire being separated by turns formed in others of said wires. 30

5. A grid electrode composed only of three or more wires positioned symmetrically about a common axis and extending substantially parallel thereto, each wire at a plurality of spaced points intermediate its ends having formed therein parallel turns intersecting said longitudinal wires and intertwined therewith at the points of intersection, successive turns in each wire being separated by parallel turns in others of said wires whereby a self-supporting cylindrical cage-like grid electrode is formed. 40
